UNITED STATES PATENT OFFICE.

HAMILTON ABERT, OF PASSAIC, NEW JERSEY.

DESIGN FOR A GOLF-TEE.

47,942.

Specification for Design.

Patented Oct. 12, 1915.

Application filed July 14, 1915. Serial No. 39,913. Term of patent 7 years.

To all whom it may concern:

Be it known that I, HAMILTON ABERT, a citizen of the United States, residing at Passaic, New Jersey, have invented a new, original, and ornamental Design for Golf-Tees, of which the following is a clear, full, and exact description.

Referring to the accompanying drawings forming a part thereof, Figure 1 is a plan view of the golf tee illustrating my new design; and Fig. 2 is a side elevation thereof.

What I claim is:

The ornamental design for a golf tee, as shown.

HAMILTON ABERT.

Witnesses:

R. S. KITTLE,
C. K. HENDERSON.
